Application July 29, 1933, Serial No. 682,862

12 Claims. (Cl. 122—210)

My invention relates to heating devices and particularly to units adapted to be applied to existing furnaces or boilers to utilize heat in the flame and products of combustion passing from a burner to the flue of the furnace.

It is usual practice when using the "gun type" of oil burners for heating furnaces, or when using other similar heating elements burning fluid fuels, to employ a fire box in the base of the furnace into which the flame and combustible gases or atomized fuel are projected. The fire box is ordinarily formed of fire brick or other refractory material which becomes highly heated or incandescent during operation and thus aids in the combustion of the fuel in the furnace.

It has been suggested heretofore that a fire box having a water jacket be connected to the boiler of the furnace for the purpose of preventing overheating of the fire box and the heat thus removed from the fire box has served incidentally to raise the temperature of the water in the boiler. It is also old to construct boilers with water legs extending down the sides of the furnace and beneath the bottom of the ash pit. However, in all previous structures including elements in the nature of water cooled fire boxes, the fire box has either been an element of special construction designed and adapted only for use in combination with a particular form of oil burner or the fire box has been cast or otherwise formed as an integral and permanent part of the furnace boiler.

So far as I am aware, no fire box heretofore made has been adapted for application to existing furnaces and boilers and capable of use with any make or style of "gun type" oil or fluid fuel burner. Furthermore, it has been necessary heretofore to make a different size and shape of fire box for every different style and size of furnace. This has made it necessary to construct a special fire box for every installation or in the alternative to supply a large variety of sizes and shapes of fire boxes and to fit the fire box to each furnace as nearly as possible from one of a large stock of various sizes, styles and shapes of fire boxes. Moreover, fire boxes which are not formed integral with the boiler have always been formed in one piece or installed as a unitary structure, and it has been difficult to introduce such fire boxes through the ash pit opening. When a water compartment surrounds the fire box the space for receiving flame as well as the size of the water jacket is necessarily limited by the size of the ash pit

opening through which the fire box has to be inserted. The fire boxes cannot be either wider or higher than the ash pit opening through which they are to be introduced into the furnace. For this reason it is not always possible to provide adequate space for combustion of the fuel within the fire box and in no case can the fire box extend upwardly sufficiently to shield the lower portions of the water legs of the boiler. As a result that portion of the water legs adjacent the bottom thereof, wherein mud and silt collect to form what is commonly termed a "mud ring" tends to become overheated and burn through.

Another and probably more important objection to the water jacketed fire boxes heretofore suggested has arisen from the fact that circulation of steam and water through the water jacket has been poor. This has been due to the fact that the portion of the water jacket extending beneath the fire box has been substantially flat and horizontal so that steam formed in the lower portion of the fire box collected on the flat upper inner surface of the water compartment adjacent the bottom of the fire box and could not readily escape. The steam therefore collected and expanded forming an insulating layer between the fire box and the water adjacent the bottom thereof. As a result the bottom of the fire box over heated and tended to burn through or warp, injuring or destroying the fire box. Even when no steam is formed the heated water in such fire boxes rises into contact with the bottom of the fire box and forms a thick layer or "skin" which prevents the cooler water in the compartment from coming into contact with the heated surfaces so that the efficiency of the element as a heat exchange device is relatively low.

In accordance with my invention these difficulties and objections to the structures of the prior art are overcome and means provided for forming fire boxes of various sizes and shapes adapted for use with any style or size of furnace. The structure may be readily applied to either existing or new furnaces and may be formed of a limited number of standard sections or parts capable of easy assembly after being introduced into the furnace. I also provide a structure so formed that steam and heated water circulate rapidly through the water compartment of the fire box bringing cool water continuously into contact with the heated surfaces and removing steam and heated water rapidly therefrom. In accordance with my in-

vention it is also possible to provide fire boxes of various widths and heights either wider or higher than the ash pit door, and of sufficient internal dimensions to insure proper combustion of the fuel, and protection of the lower portion of the water legs of the boiler.

My invention embodies a further feature which also is new in the art in that the water compartment of the fire box may be connected to auxiliary heating means adapted to take up additional heat from the flame and products of combustion in the furnace and this heat is imparted to water passing to the boiler so that a water circuit is established which induces rapid circulation of the whole body of water in the boiler. The auxiliary heating means may take various forms and may if desired embody features and elements of the invention described in my co-pending application Serial No. 662,403, filed

20 March 23, 1933.

One of the objects of my invention is to provide a simple and inexpensive fire box having a water compartment therein.

Another object of my invention is to provide 25 elements adapted to form fire boxes of various sizes and shapes.

A further object of my invention is to provide a fire box having a water compartment and so formed as to induce rapid circulation of steam 30 and heated water in said compartment.

A further object of my invention is to provide a fire box adapted to be applied to existing furnaces or boilers and capable of assembly within the ash pit of the furnace whereby a fire box 35 of greater width or height than the ash pit opening may be provided.

Another object of my invention is to provide a water box having a compartment adapted to receive water and having auxiliary heating elements 40 communicating therewith and serving to utilize additional heat in the products of combustion passing to the flue of the furnace.

Other objects of my invention are to increase the absorption of heat by water circulated 45 through the boiler of a furnace, to provide a simple and inexpensive heating device adapted to be applied to a wide variety of styles and sizes of furnaces, to reduce the expense of operating furnaces and to utilize heat otherwise wasted in the operation of furnaces and boilers using fluid fuels.

These and other objects and features of my invention will appear from the following description thereof in which reference is made to the accompanying figures of the drawings which 55 illustrate typical embodiments of my invention.

In the drawings:

Fig. 1 is a vertical sectional view of one form of fire box and auxiliary heating unit applied 60 to the boiler of a furnace in accordance with my invention.

Fig. 2 is a plan view of the form of auxiliary heating tubes and connections therefore illustrated in Fig. 1.

Fig. 3 is a detailed sectional view of one form 65 of connection between a heating tube and the water compartment of the fire box.

Fig. 4 is a plan of the form of fire box shown in Fig. 1.

Fig. 5 is a transverse sectional view of the fire box taken on the line 5-5 of Fig. 4.

Fig. 6 is a longitudinal sectional view taken 70 on the line 6-6 of Fig. 4.

Fig. 7 is a side view of the exterior of the form 75 of fire box shown in Fig. 1.

Fig. 8 is a diagrammatic end view of a fire box and alternative form of auxiliary heating means.

Fig. 9 is a diagrammatic side view of the structure shown in Fig. 8.

Fig. 10 illustrates an alternative fire box construction, and

Fig. 11 illustrates an alternative form of a front end section of a fire box in accordance with my invention.

In the form of my invention illustrated in Figs. 1-7 of the drawings I have shown a furnace 2 having a boiler 4, a fire box 6 and a combustion space 8 above the fire box and beneath the crown sheet 10 of the boiler. A burner 12 for heating the furnace extends through an opening in front of the ash pit and into the front end of the fire box. Flame and products of combustion are projected into the fire box and pass upwardly through the combustion space and over heating tubes 14 of an auxiliary heating device into contact with the crown sheet of the boiler. The hot gases and products of combustion then flow through openings 16 in the crown sheet into the upper pass 18 of the boiler and thence through the flue 20 to the chimney or stack. It will, of course, be understood that the particular form of furnace and boiler shown have been chosen only for purpose of illustration since the device may be applied to any other suitable type of furnace as desired.

The form of fire box illustrated in Figs. 1, 4, 5, 6, and 7 is made up of a plurality of independent sections connected together to form both the fire box and the surrounding water compartment. As shown, the fire box comprises two intermediate sections 22, an end section 24 and a front section 25. Any number of intermediate sections may be used depending upon the size of the furnace, the size of the fire box and the size and style of burner used in the particular installation in question. The intermediate sections are identical in construction, each being in the form of a hollow U-shaped casting having substantially straight, vertical inner side 4 walls 26 and a curved or sloping bottom 28 joining the side walls. The water compartment 30 of each section is formed of an outer shell 32 connected to the inner side walls and bottom by webs 34 at the front and back of the casting. The upper ends of the inner walls and the outer shell are joined at the top by the portion 36. Each section thus provides a water compartment presenting an upper inner face adjacent the bottom of the fire box which slopes or curves upwardly so that there is no chance for steam bubbles to collect on the lower surface thereof. Steam and heated water in the water compartment therefore, pass readily upward from the lower to the upper portion of the compartment 60 insuring rapid circulation of the steam and water therethrough. In this way I not only avoid any possibility of steam insulating the bottom of the fire box from the water but I also induce rapid flow of hot water and steam over the upper inner face of the water compartment of the fire box. The water is thus kept in constant and vigorous circulation bringing cold water into contact with the heated inner face of the compartment and effecting rapid and efficient heat exchange.

The webs 34 at the front and back of the casting are provided with upper ports 38 and lower ports 40 providing communication between the successive sections 22 and the end section 24 and the front section 25. The corresponding ports in 75

adjacent sections register and may be connected by any suitable means such as push-nipples 42 engaging inwardly tapering walls of the ports 38 and 40. The sections themselves are clamped together and held in position by bolts 44 extending through bolt holes in lugs 46 at the top of the castings and by bolts 47 extending through lugs 48 near the bottom of the castings. These bolts serve to draw the castings together and cause the push-nipples to seat firmly in the ports 38 and 40, so that a rigid water tight structure is produced. Any suitable pipe compound or the like may be applied to the push nipples in the usual manner to prevent possible leaking, if desired.

The intermediate sections 22 are connected to an end section 24 in the same manner as they are connected to other intermediate sections. The end section 24, as shown in Figs. 1 and 4, is in the form of a hollow casting having an inner vertical face 50 which is curved laterally to present a rounded surface to the flame and heated gases passing over the same. The lower portion 52 of the end face is curved or sloped inwardly and downwardly so as to direct the flames and products of combustion up over the auxiliary heating tubes 14 and against the crown sheet of the boiler.

The compartment 54 of the end section is formed by an outer shell 56 connected to the inner wall of the casting by web 58 forming a closed front for the compartment. The web 58, like webs 34 of the intermediate sections, is provided with upper ports 62 at the top of the compartment and with lower ports 64 adjacent the bottom of the compartment at either side of the center thereof. The ports 62 and 64 provide communication between the water compartment 54 of the end section and the water compartment 30 of an adjacent intermediate section. The inner face 50 and the outer shell 56 are connected by a portion 65 which may be tapped for connections with heating tubes 14 of an auxiliary heating device if desired.

In Fig. 10 I have illustrated a modification of the form of intermediate and end sections described above in which central sections 66 are provided for forming fire boxes of unusual width. These sections may be joined to lateral intermediate sections 68 and to central end sections 70 by means of push-nipples or otherwise as in the construction described above. The central section is formed with a curved upper inner surface for the water compartment to insure lateral flow of steam and heated water over the surfaces thereof and therefore even when using relatively wide fire boxes embodying my invention all danger of overheating and inadequate circulation of the water through the water compartment is avoided.

Ordinarily I prefer to provide a separate front section 25 in the form of a casting similar to the intermediate castings 22 in transverse section but of less depth (lengthwise of the fire box). The rearwardly facing web of the front section is similar in form to the webs 34 of the intermediate sections in that it is provided with upper ports 38 and lower ports 40 for connection with an adjacent intermediate section. The front web 73 however is provided only with lower ports 74 and a centrally located cleanout port 76. The ports 74 are preferably threaded to receive the threaded end of an inlet pipe, and port 76 is formed to receive a threaded plug or other stopper. The front section is provided with lugs

similar to the lugs 46 and 48 of the intermediate sections for securing the front section in place. If preferred, the front section 25 may be omitted and suitable plugs inserted into the upper ports 38 of the foremost intermediate section. Inlet 5 pipes to supply water to the water compartment of the fire box may then be attached to each of the lower ports 40 or I may provide a suitable plug for one of the lower ports 40 and introduce water into the water compartment through only one of the lower ports. With such an arrangement only two forms of casting are required for assembling fire boxes of various sizes, one for the intermediate sections and one for the end sections.

In Fig. 11 I have shown an alternative form of front section 78 which is similar in its general shape to the end section 24 but is provided with an opening 80 through which the burner 12 projects. This construction provides additional 20 surfaces for the absorption of heat from the flame and products of combustion and prevents reflected heat from heating up or injuring the front of the ash pit or the burner.

The sectional construction described above may be quickly and easily assembled by the ordinary mechanic. By connecting together any desired number of intermediate sections 22 it is possible to provide a long fire box for a deep furnace or a relatively short fire box for a short or round 30 furnace. If, for any reason, it is necessary to remove or to add sections to the fire box this may be done very readily without destroying or discarding the remaining sections of the fire box. The manufacturer and dealer then need 35 keep in stock only one size of intermediate section and one size of end section for all length of fire boxes. It will, of course, be understood that the castings may be made in various widths, if desired, so that two or three sizes of intermediate and end sections will constitute the entire stock required to enable any dealer to supply a water jacketed fire box for any size or style of furnace. This flexibility of construction and assembling greatly reduces the investment required to meet the demand on manufacturers 40 and dealers for fire boxes of this character.

Since each section of the fire box is comparatively small, it is not difficult to introduce the sections through the ash pit opening. These are 50 assembled in place one after the other, inside ash pit space, until a fire box of the desired size has been built up within the furnace. The large size and difficulty encountered in placing and installing water jacketed fire boxes heretofore 55 has often rendered it impossible to use fire boxes of sufficient width to obtain the best results with a furnace or oil burner. When there is a water compartment about the fire box, the width of the inner flame receiving space is necessarily 60 considerably less than the width of the ash pit opening through which the fire box must be inserted. In my construction, the width of the fire box may be considerably increased and may, if desired, have a flame receiving space that is 65 wider than the ash pit opening since the sections are introduced one at a time and assembled within the enlarged area of the ash pit. The height of the fire box may also be greater than that of the ash pit opening and ordinarily is sufficient to protect the lower portions of the water legs from direct contact with the flames. In this way, I may install fire boxes having water compartments in furnaces which heretofore could not be provided with a fire box of this 70 75

character because of the limited size of the opening through which the fire box had to be introduced. I may also provide fire boxes of suitable size and form to insure proper combustion in furnaces which previously were seriously handicapped by the limited space available for the flame within the fire box, and the danger of burning out the lower portions of the water legs where mud and silt had collected.

10 I prefer to have the fire box lined with refractory material in each instance for the reason that such refractory lining apparently aids in the combustion of oil or other fuel. The use of refractory lining also prevents the fire box from being cooled to such an extent that the temperature of the flame is reduced sufficiently to interfere with proper combustion. Any suitable refractory material may be used, and it may be applied either to the inner curved faces of each section or to the inner face of the assembled fire box in the form of a plaster or a cement. However, I prefer to use prepared or pre-formed bricks or tiles 82 as illustrated in Figs. 1, 4 and 5 of the drawings. For this purpose, the bricks or tiles to be applied to the lower portion of the fire box are formed on their opposite edges with projecting tongues 84 or with tongue and groove formation to provide an interlocking connection between the adjacent bricks. The bricks 86 extending about the upper edge of the fire box are preferably formed with inwardly projecting portions 88 which serve to confine the flame as it passes out of the fire box and direct the same upwardly in the center of the combustion space.

20 That portion of the bricks extending over the upper edge of the top of the castings is provided with a recess 90 engaging a projection 92 on the inner rim of the casting to prevent the bricks from falling or tipping inward away from the walls of the fire box. The lower edge of the bricks also is formed to prevent dislocation of the bricks 86 with respect to those extending over the bottom of the fire box, and for this purpose a lower edge 94 may be inclined as shown in Fig. 5 to engage a correspondingly inclined upper edge on the adjacent bricks. With this construction, the bricks or tiles may be shipped and handled separately from the casting sections and the thickness of the refractory material will be uniform in all installations.

25 The bricks, tiles, cement or other refractory material used may be formed of any desired material but I prefer to use material of a refractory nature which at the same time has a relatively high heat conductivity or heat transferring capacity so that the water in passing through the compartment of the fire box will take up considerable heat and become hot or even boil. Carbide is a typical material having the desired refractory and heat transferring properties.

30 While it is possible to use a fire box embodying my invention independently of the water circuit of the furnace boiler, I prefer to connect the water compartment of the fire box with the upper and lower portions of the boiler. In this way water heated in the compartment will rise upwardly to the upper portion of the boiler and cool water from the lower portion of the boiler will be drawn into the water compartment. The water circulating through the compartment of the fire box is preferably the coolest water in the system so that the heat absorbed from the flame and products of combustion in the fire box is utilized to raise the temperature of the boiler water and increase the circulation of the

35 water there through. The amount of heat taken up by the water in the system therefore is materially increased. For this purpose, an inlet pipe 96 is provided which communicates with the lower portion of the water leg of the boiler and extends through the front of the ash pit or the base of the boiler and is connected with the front section 25 of the fire box. The inlet pipe 96 is threaded into the lower port 74 of the front section or may be otherwise secured to and connected with the water compartment of the fire box. If preferred, a second inlet pipe may be provided for connection with the other lower port 74 of the front section to insure an ample supply of water to the water compartment in the fire box. In every case where possible, it is desirable to have the inlet pipe 96 extended through the base of the furnace rather than through the water legs of the furnace for the reason that drilling and sealing of such connections is difficult and involves considerable expense.

40 As shown in Fig. 1, the water compartment of the fire box may be connected with an auxiliary heating device comprising heating tubes 14 connected to the end section 24 and extending upwardly through the combustion space 8 to an upper header 98. The tubes 14 may be arranged about the arcuate upper edge of the end section 24 and they may, of course, also be connected to one or more of the intermediate sections if desired. As illustrated in Fig. 3, the lower end of each pipe may be secured to the top portion 65 of the end section by means of a castellated bushing 100 threaded into a recess in the top portion 65 and engaging the flared lower end 102 of the tube. This construction and connection between the heating tubes and a header is shown and described in my co-pending application referred to above.

45 The tubes 14 of the form of auxiliary heating device shown in Fig. 1, extend substantially vertically and horizontally through the combustion space 8, and the upper ends thereof are connected to the header 98 by a castellated bushing similar to that employed for connecting the lower ends of the tubes to the end section 24. The header 98 is formed with a series of stepped faces 103 arranged in a generally arcuate formation corresponding to the arcuate end of the end member 24 of the fire box so as to enable the heating tubes 14 to be interchangeably assembled. Thus the heating tubes may all be of the same length and configuration and their manufacture and assembly is greatly simplified.

50 As illustrated in Fig. 2, the upper header 98 is provided with one or more outlet openings 104 to which delivery pipes 106 may be connected for discharging heated water from the header into the steam space 108 at the top of the boiler. I prefer to have the discharge end of the pipe 106 terminate at or above the water line in the boiler in order that resistance to the discharge of heated water and steam from the header and heating tubes may be reduced to a minimum.

55 The location of the header 98 may be varied considerably, but, as illustrated, it is convenient to have the header located adjacent the fire door so that the discharge pipe 106 may extend through an opening in the fire door rather than pass through one of the side legs of the boiler or through the crown sheet thereof.

60 The form and arrangement of the heating tubes used may be altered as desired for any installation and may have any shape or form of connection adapted for use in any particular instance.

The number and point of connection of the tubes to the fire box compartment and to the boiler may also be varied since it is only necessary that there should be no downwardly extending portions or other parts which might form steam or air traps which would prevent or interfere with the ready circulation of water through all parts of the water circuit.

In my co-pending application referred to above, I have shown and described a very efficient type of heating unit adapted to be applied to existing or new furnaces for increasing the absorption of heat from the flame and products of combustion in the combustion space of the furnace. The structure described therein is formed with lower and upper headers, having heating tubes extending between the same. Such a structure is also adapted for use in combination with the fire box of the present invention. As illustrated in Figs. 8 and 9, a heating unit embodying features of the invention described in said co-pending application is shown as employed in conjunction with the water jacketed fire box described above, in place of the auxiliary heating unit illustrated in Fig. 1. When using this type of heating unit, it is preferable to connect the lower headers 110 of the unit to each side of the water compartment for the fire box. Any suitable connection, such as an elbow 112, may be used for this purpose. I prefer to provide the connection between the water compartment of the fire box and the headers 110 at a point remote from the inlet pipe 96 which supplies water from the boiler to the fire box compartment. The discharge pipe 106 may then be connected to the opposite end of the upper header 114 of the unit so that a relatively long path of travel is provided for the water circulating through the fire box and auxiliary heating unit. Thus, for example, water drawn from the lower portion of the boiler will be introduced through the inlet pipe 96 at the front end of the water compartment for the fire box and will pass through various sections thereof to that section 22 to which the header 110 is connected. The water thus heated will then pass through the elbows 112 into the lower headers of the auxiliary heating unit and through the connecting tubes 14 which extend upwardly from the lower header 110 to the upper header 114. The water together with any steam produced will thus be subjected to still further heating and will be discharged from the opposite end of the upper header 114 through the discharge pipe 106 and will pass into the upper portion of the boiler at a point 55 at or adjacent the water level of the boiler.

This construction provides a very large surface for absorption of heat from the flame and products of combustion in the furnace and insures rapid and vigorous circulation of the whole body of water in the boiler. The increased velocity of flow of the water over the surfaces of the boiler greatly increases the amount of heat absorbed from the hot walls of the boiler itself and for this reason the gases and products of combustion which pass out of the flue of the furnace are very much reduced in temperature and the efficiency of the furnace is greatly increased.

As shown in Fig. 9 when the furnace is comparatively deep the fire box will not extend the full length of the furnace and the auxiliary heating unit may extend rearwardly of the fire box and have the back end thereof supported on brick 116 or any other suitable support. With furnaces of this type the upward pass from the combus-

tion space to the flue or upper passes of the boiler is generally located at the rear of the furnace so that the flame and products of combustion pass over the heating tubes to an even greater extent than if they were located directly over the fire box. The discharge pipe 106 in this construction may then extend through the pass 118 in the upper portion of the boiler as in the construction of my co-pending application.

Although I prefer to form the fire box as described above in sections, certain features thereof and the combination of a fire box of this character with a boiler may be utilized even when the entire fire box is formed in a single unit. Furthermore, it is not essential that the fire box sections be cast since they may also be formed of sheet steel or other material and welded or otherwise constructed if desired.

While I have illustrated and described certain preferred forms of my invention, it will be understood that various features thereof may be changed materially in form and construction without departing from the spirit and scope of my invention.

I claim:

1. A unit adapted to be applied to existing boilers fired by oil burners to increase the absorption of heat from the flame and products of combustion passing therethrough, comprising a fire box having a compartment adapted to receive water extending about the bottom and sides of the fire box, the upper inner surface of which compartment presents an inclined face, heating tubes extending transversely of the path of flame and products of combustion passing from said fire box and into contact with said boiler, means connecting the lower end of the heating tubes to the compartment in said fire box, and means connecting the upper ends of said heating tubes to the upper portion of said boiler.

2. A unit adapted to be applied to existing boilers fired by oil burners to increase the absorption of heat from the flame and products of combustion passing therethrough, comprising a member having a compartment adapted to receive water, heating tubes positioned above said member and extending transversely of said flame and products of combustion, a lower header to which the lower ends of said heating tubes are connected communicating with the compartment in said member, an upper header to which the upper ends of said heating tubes are connected, a connection between the lower portion of said boiler and the compartment in said fire box and a connection between the upper header and the upper portion of the boiler connected to a point on said boiler which is not exposed to heat from said oil burner.

3. The combination comprising a boiler having a combustion chamber, an oil burner for heating said boiler discharging flame into said combustion chamber, a fire box adapted to be applied to the boiler extending about the sides, bottom and end of the combustion chamber in position to be heated by flame from said oil burner, said fire box being formed of a plurality of hollow sections each having a water compartment therein connected to a water compartment of an adjacent section, the upper inner surface of the water compartment of each section sloping from the center toward the side of the fire box to induce flow of steam and heated water from the lower to the upper portion of the compartment therein and means connecting the water compartment of one section to the lower portion of the boiler and

connecting the water compartment of another section to the upper portion of the boiler.

4. The combination comprising a boiler having a combustion chamber, a fire box having a

5 water compartment therein located in said combustion chamber, a plurality of interchangeable heating tubes of substantially the same length and form communicated at their lower ends with said fire box and a header to which the upper 10 ends of said heating tubes are connected communicating with said boiler.

5. In combination with a fire box having a compartment for receiving water and formed with a curved portion, a plurality of heating tubes 15 connected at their lower ends to the curved portion of said fire box and a header to which the upper ends of said heating tubes are connected, said header having a portion thereof similar in configuration to the curved portion of said fire 20 box.

6. The combination comprising a boiler having a combustion space therein, an oil burner for heating said boiler, a member having a water receiving compartment therein which member is

25 spaced from the oil burner and located in part at least below the same, a connection from the lower part of the boiler to said compartment, heating tubes connected to the upper portion of said member and extending transversely of the path of flow of flame and products of combustion passing from the oil burner over the surface of the boiler and means connecting said heating tubes to the upper portion of the boiler, whereby 30 a circuit is provided for the flow of water from the lower portion of the boiler through the compartment in said member and thence through the heating tubes to the upper portion of the boiler.

7. In combination with a boiler having an ash 40 pit door opening and a combustion chamber extending above said opening and provided with a fire door opening, an oil burner from which flame and products of combustion pass upwardly through said chamber, a supplemental water 45 heating device having a hollow water receiving portion thereof extending upwardly at one side of said chamber with the upper portion thereof above the ash pit door opening and in position to be heated by flame and products of combustion 50 passing from said oil burner over the boiler surfaces and means connecting said supplemental heating device to the boiler to provide for the circulation of boiler water therethrough, said means extending from the lower portion of the 55 boiler through an unjacketed portion thereof not substantially above the ash pit door opening and other means extending from the upper portion of the supplemental heating device through the fire door opening to the upper portion of the 60 boiler.

8. In combination with a boiler having a combustion chamber, an oil burner located at one side of the boiler adjacent the bottom thereof discharging flame and products of combustion into 65 said combustion chamber to heat the boiler surfaces, and a supplemental heating device communicating with the upper and lower portions of the boiler located in the combustion chamber and formed with a water receiving portion positioned on the side of the combustion chamber opposite said oil burner with spaced water conducting members extending upwardly at one side of said chamber and inwardly toward the center 70 of the chamber over the flame and products of 75

combustion issuing from said oil burner and passing upwardly over the boiler surfaces.

9. The combination comprising a boiler having a combustion chamber, an oil burner for heating said boiler extending into the front of the 5 boiler adjacent the bottom thereof, a member having a water receiving compartment therein located in the combustion chamber adjacent the rear of the boiler and opposite the oil burner, a connection from the lower part of the boiler to 10 said compartment, spaced tubular heating elements communicating with said member and extending upwardly and forwardly therefrom in the combustion chamber and in the path of flow of flame and products of combustion passing from 15 the oil burner over the surface of the boiler and means connecting the upper ends of said tubular elements to the upper portion of the boiler, whereby a circuit is provided for the flow of water from the lower portion of the boiler 20 through the compartment in said member and thence through the tubular elements to the upper portion of the boiler.

10. In combination with a boiler having a combustion chamber and water legs extending 25 downwardly about the same, an unjacketed portion below the water legs of the boiler and an unjacketed portion above the bottom of the water legs, an oil burner discharging flame and products of combustion into the combustion chamber 30 so that they pass upwardly therethrough, a supplemental heating device located within the combustion chamber comprising a hollow body through which boiler water is circulated having a portion thereof extending upwardly at the rear 35 of the combustion chamber above the bottom of the water legs and a communicating water receiving portion thereof extending forwardly therefrom over flame and products of combustion passing upwardly through the combustion 40 chamber, and connections between said body and the boiler completing a circuit for the flow of boiler water therethrough including a conduit communicating with the lower portion of said body and passing from the lower portion of the boiler 45 through said unjacketed portion thereof below the water legs and a conduit extending from the upper portion of said body through said unjacketed portion of the boiler above the bottom of the water legs to the upper portion of the boiler. 50

11. In combination with a boiler of the vertical flue type having a combustion chamber through which gases pass substantially vertically and water legs extending downwardly about the same, an unjacketed portion below the water legs of the 55 boiler and an unjacketed portion above the bottom of the water legs, an oil burner discharging flame and products of combustion into the combustion chamber so that they pass upwardly therethrough, a supplemental heating device located within the combustion chamber comprising a hollow body through which water is circulated having at least a portion thereof positioned above the bottom of the water legs and extending substantially horizontally in said chamber so that 60 flame passing substantially vertically through the combustion chamber passes over the same and connections between said device and the boiler completing a circuit for the flow of boiler water therethrough including a conduit communicating 65 with the lower portion of said body and passing from the lower portion of the boiler through said unjacketed portion thereof below the water legs and a conduit extending from the upper portion of said device through said unjacketed portion of 70 75

the boiler above the bottom of the water legs to the upper portion of the boiler.

12. In combination with a boiler having a combustion chamber, an oil burner located at one side of the boiler adjacent the bottom thereof discharging flame and products of combustion into said combustion chamber to heat the boiler surfaces and a supplemental water heating device provided with connections extending from 5 said device to the exterior of the boiler and communicating with the upper and lower portions thereof to provide a path for the circulation of 10 boiler water through said device, said device being located in the combustion chamber and formed with a hollow water-receiving portion positioned on the side of the combustion chamber opposite said oil burner and with a communicating hollow water receiving portion extending substantially horizontally over flame and products of combustion issuing from said oil burner and passing upwardly through the combustion chamber. 10
